 Minn., assignor to Joseph R. Brink, Minneapolis, Minn.
 Filed Dec. 9, 1963, Ser. No. 329,318
 6 Claims. (Cl. 316—23)

This invention relates generally to the production of filament lamps, and more particularly it relates to a novel tool and method for positioning the filaments in the bulbs of filament lamps in their proper focal positions.

Generally, the tool and apparatus of the present invention comprises a base member, a parabolic reflector carried by the base member, a seat defined by the base member and adapted to receive the bulbs of the lamps to be adjusted, means for initially adjusting the reflector relative to the seat by the use of a master filament lamp, means for releasably retaining the bulbs of the lamps to be adjusted against the seat, whereby the filaments of the lamps may be adjusted by moving the stem until a given portion of the filament intersects its similarly given portion of the filament image produced by said reflector when viewing the filament from a generally lateral viewpoint; and the present invention also comprises a novel method for accomplishing the above-noted adjustment of the lamp filaments.

It is known that glare from electric filament lamps results from the lamp filaments being incorrectly positioned within the lamps and not in the proper focal position. The glare from electric filament lamps has been a long known problem, particularly with electric filament lamps of the seal beam headlight type for automotive vehicles; and the elimination of glare from filament lamps would permit the elimination of the costly fluting of the lamp lenses, together with the elimination of the dimming equipment for filament lamps used on automotive vehicles.

In view of the above known problems and characteristics of filament lamps, it is an important object of the present invention to provide a tool and apparatus for the quick and easy positioning of the filaments in the bulbs of filament lamps in their proper focal positions during manufacture.

Another important object of the present invention is the provision of a novel method for accomplishing the above-noted adjustment or filament positioning of the lamps.

Another object of the present invention is the provision of a novel tool or apparatus and novel method for correctly positioning filaments in electric lamps which initially utilizes a master filament lamp having a generally perfectly focused filament, and which method and apparatus may be used to manufacture innumerable quantities of lamps having generally perfectly focused filaments, after the initial adjustment of the tool.

A further object of the present invention resides in the provision of a novel tool and method for the production of filament lamps having generally perfectly focused filaments so as to eliminate the above-noted problem of glare.

Other objects of the present invention reside in the provision of a novel method and apparatus for the production of filament lamps having generally perfectly focused filaments which are simple in their operation, may be economically utilized, and also provide for the efficient and economic production of filament lamps.

Other objects and advantages of the present invention will become apparent from a consideration of the following detailed specification, appended claims and attached drawings.

Referring to the drawings, wherein like reference characters indicate like parts or elements throughout the several views:

FIG. 1 is a view in side elevation of the tool and apparatus for the present invention;

FIG. 2 is a reduced view in rear elevation thereof;

FIG. 3 is a view in front elevation thereof;

FIG. 4 is an enlarged view in section taken on the line 4—4 of FIG. 3;

FIG. 5 is a reduced view corresponding to FIG. 4 of the drawings, but showing a filament lamp positioned thereagainst and also showing some of the steps of the novel method of this invention;

FIG. 6 is a view corresponding to FIG. 5, and showing further steps of the novel method of this invention, some portions of the structure being broken away;

FIG. 7 is a view in section of a filament lamp showing still further steps of the novel method of this invention;

FIG. 8 is a view in side elevation of an alternative type of tool for another type of filament lamp;

FIG. 9 is an enlarged view in perspective of the structure shown in FIG. 8 showing the overlapping position of the filament and the filament image, as described hereinafter; and

FIG. 10 is a view in perspective corresponding to that shown in FIG. 9, but showing the intersecting position of the filament and the filament image, as described hereinafter.

It is noted that the terms side elevation, rear elevation and front elevation as used in describing the above figures of the drawings are used only in a relative sense with respect to one another for convenience of description, and are not intended to limit the actual positions of the devices as they may be utilized.

Referring more particularly to the drawings, the novel tool and apparatus of the present invention shown particularly in FIGS. 1-4 of the drawings comprises a tri-section base member, represented generally by the reference numeral 1. The three sections of the base member 1 are each represented by the reference numeral 2, and the inner surfaces 3 thereof are formed to generally define portions of a paraboloid. The base member 1 further comprises a tri-section insert plate corresponding generally to the configuration of the tri-sections 2 and secured thereto by suitable fasteners 5. The insert plate 4 is further formed to define an elongated generally tubular handle portion 6, as shown particularly in FIG. 4 of the drawings.

In accordance with this invention, the tool or apparatus further comprises a parabolic or paraboloidal reflector, represented generally by the reference numeral 7, carried by the base member 1 and mounted therein for adjustable movements with respect thereto. The tool further comprises a plurality of spaced seat elements 8, each one defined by a different one of the sections 2 of the base member 1. The seat elements 8 are sometimes referred to herein collectively as a seat, and it is noted that in some applications, the seat may be defined by the outer circumferential edge portion 9 of the paraboloidal reflector 7. The reflector 7 is mounted by suitable means, described particularly hereinafter, within the base member 1 for longitudinal adjustment relative to the base member 1, and also relative to the seat element 8. The reflector 7 defines an axially outwardly extending spindle 10 of smaller diameter than the bore of the handle portions 6 of the base member 1, and the end portion of the spindle 10 fits within a bearing-acting bore defined in the inner end portion 11 of an adjustment screw rod 12. The adjustment screw rod 12 is screw threaded within the bore of the handle portion 6 and may be adjusted by a suitable tool, not shown, adapted to fit the slotted outer end portion 13 thereof. The reflector 7 is held in its desired

adjusted position by means of a set screw 14 screw threaded into the handle portion 6, as shown particularly in FIGS. 4 and 5 of the drawings.

The tool and apparatus of the present invention further comprises means for releasably retaining the bulbs of the lamps to be adjusted against the seat or seat elements 8 of the tool. Said means comprises a plurality of inwardly biased roller elements, each represented by the reference numeral 15, and each one positioned generally adjacent a different one of the seat elements 8, as shown particularly in FIGS. 1 and 3 of the drawings. The outer generally cylindrical surface of each of the roller elements 15 is generally arcuately formed for suitable engagement with the bulb surface of the lamp to be adjusted. As shown in detail in FIGS. 1 and 4 of the drawings, each of the roller elements comprises a bifurcated bracket 16 for mounting the associated roller and a longitudinally extending spring member 17 adjustably secured to the associated section 2 of the base member 1 by means of an elongated bracket 18 having a channel defined therein. It is further noted that the roller elements 15 are located longitudinally of the base member 1, or axially of the paraboloidal reflector 7, for engagement of the bulb surfaces of the lamps to be adjusted at positions over the greatest transverse diameter of the bulbs of said lamps, as shown for example in FIGS. 5 and 6 of the drawings. The roller elements 15 are spring biased in an inward direction between a position in engagement with the bulb surfaces of the lamps to be adjusted, as shown by full lines in FIG. 5, and outer positions upon removal or insertion of the lamps, as represented by the dotted lines in FIG. 5 of the drawings.

When using the tool or apparatus of the present invention, the reflector 7 is initially adjusted with respect to the base member 1 by use of a master filament lamp, not shown, of the same size as the lamps to be adjusted and having a filament previously determined to be perfectly focused. The master filament bulb, not shown, is positioned within the tool and the reflector 7 is thereafter adjusted by means of the adjustment screw rod 12 to a position wherein a given portion, such as the tip, of the filament of the master filament lamp intersects a similarly given point or portion of the filament image produced by the reflector when viewing the filament from a generally lateral viewpoint. When the reflector 7 has been so adjusted, the same is held to its desired position by means of the set screw 14 and further adjustment of the reflector 7 will be unnecessary for later use in the production of filament lamps of the same diameter as the master filament lamp. Thereafter, the tool or apparatus of the present invention may be used for the production of filament lamps having generally perfectly focused filaments, by inserting the lamps within the roller elements 15 and against the seat elements 8. Then, as will be particularly described hereinafter, the lamps are adjusted by moving the stem thereof until a given portion, such as the tip of the filament intersects a similarly given portion of the filament image produced by the reflector 7 when viewing the lamp filament from a generally lateral viewpoint.

The tool or apparatus of the present invention further comprises means for ejecting the adjusted lamps from the tool, and as shown particularly in FIGS. 1, 2 and 4 of the drawings, said ejection means comprises a plurality of ejector rods 19. The ejector rods 19 have axially extending inner portions 20 received within corresponding slots 21 defined in the handle portion 6 of the base member 1. The ejector rods 19 also comprise intermediate transverse portions 22 and outer axially extending portions 23 received within corresponding bearing bores 24 within the sections 2 of the base member 1, as shown particularly in FIGS. 2 and 4 of the drawings. Upon pushing button 25 adjacent the end of the handle portion 6, the outer portions 23 of the ejector

rods 19 will engage the bulb of the lamp within the tool and eject the same.

Method

With respect to the novel method of the present invention, the same may be practiced according to the following specific steps some of which may be eliminated without deviating from the scope of this invention. Initially, the tool is adjusted by placing therein a master filament lamp of the same size and having a generally perfectly focused filament, and the reflector 7 is adjusted by means of the adjustment screw rod 12 so as to perfectly align the filament image in the mirrored reflector 7 with the filament of the master filament lamp. Then, the tool may be thereafter used to properly adjust the filaments of a practically infinite number of lamps of the same size as the tool which has been pre-adjusted by the master filament lamp. This is done with each lamp to be so adjusted by first mounting or placing the bulb 27 within the tool, and then the filament carried by the stem 26 is placed within the bulb 27 through the neck 28 thereof. Of course, the filament could be placed within the bulb 27 prior to mounting each lamp in the tool. In any event, the outer generally spheroidal surface of the filament carrying bulb 27 is positioned against the above-noted seat of the tool.

Continuing with the procedure or method for properly adjusting the filament of each lamp, after the filament carrying stem 26 has been placed within the bulb 27, the stem is adjusted so as to slightly overlap (approximately $\frac{1}{8}$ " in most cases) the filament image produced in the mirrored reflector 7, as particularly shown in FIG. 5 of the drawings. Then, the bulb neck 28 (dotted lines in FIG. 5) and the flared portion 29 of the stem 26 are heated so as to seal the bulb neck 28 to the stem 26. Then, the excess or the major portion of the bulb neck 28 (dotted lines in FIG. 5) is removed. This may be done by applying pressure (approximately 4 pounds) to the neck 28, heating the same and then tapping the neck 28 to remove it. The next step is to reheat the remaining portion 30 of the bulb neck 28 and the adjacent sealed portion 29 of the stem 26, after which the filament is readjusted to the position illustrated in FIG. 6 of the drawings, wherein the stem 26 has been moved, such as by gripping the extended evacuating portion 31 thereof, until a given end portion of the filament intersects a similarly given portion of the filament image produced by the mirrored reflector when viewing the filament from a generally lateral viewpoint. The respective lines of sight used by the operators when aligning the filament and the filament image are illustrated by broken lines in FIGS. 5 and 6 of the drawings, the same being only intended to be illustrative of the invention. By the use of the above-method, every one of the lamps produced will have a perfectly focused filament, and the word perfect or generally perfect is intended to mean vastly improved perfection in the proper placement of the filament over the previous practice, it being recognized that the word perfect may have various meanings, including microscopic or nearly infinitesimal variations only ascertainable under very exacting laboratory conditions.

After the filament has been adjusted to its proper and desired location in the above manner so as to eliminate glare, the interior of the bulb 27 is evacuated in the usual manner through the evacuating portion 31, and the evacuating portion 31 is then sealed, in the usual practice. Then, the proper lamp base 32 (see FIG. 7) is mounted on the lamp, proper contact being made with the filament leads 33, 34. See FIGS. 5-7.

Other embodiments

A novel filament has been disclosed in the present invention, the same comprising a pair of axially spaced filament coils 35, 36 connected in series with a support wire 37 connected therebetween and engaging the end

portion of the stem 26, as shown for example in FIG. 6 of the drawings. The axially outer coil 36 is connected to the filament lead 33, and the axially inner end coil 36 is connected to the filament lead 34. It is noted that the relative size of the filaments shown in the drawings has been greatly exaggerated so as to particularly illustrate the construction thereof.

A modified embodiment of the tool and apparatus of the present invention is shown in FIGS. 8-10, which is a tool particularly constructed for use with filament lamps having a spherical bulb, such as smaller sizes of filament lamps, not having their own lens as is shown in FIGS. 5-7. In this embodiment, the tool body 38 has its reflector surface 39 ground to the desired configuration relative to a master filament lamp having a generally perfectly focused filament, and the same is not adjustable as is the tool initially described above. Suitable spring biased retainer elements 40 are secured to the tool body 38, as illustrated in FIG. 8, for example. Otherwise, the practice of the present invention is the same with the embodiment shown in FIGS. 8-10 as in the embodiment first described above. Further, the parts or elements of this embodiment shown in FIGS. 8-10 which correspond to like or respective parts or elements of the embodiment shown in FIGS. 1-7 are denoted by the use of the same numerals with prime marks added thereto.

With respect to all of the above, it is further noted that the sight lines (broken lines in the drawings) are for illustration only; and generally any convenient line of sight may be selected and still give satisfactory results, having in mind the refraction through the bulb and/or lens (if any) of the lamp. The refraction is not consequential from a broad standpoint since refraction is also a factor when making the original adjustment with the master filament lamp.

With respect to the operation of this invention, the same has been implicitly described above. It is also noted that this invention has been tested and found to be completely satisfactory for the accomplishment of the above-noted objects; and while preferred embodiments thereof, in which the principles of the present invention have been incorporated, have been shown and described above, it should be specifically understood that the same may be modified without departure from the scope and spirit of the appended claims.

It is claimed:

1. A tool for use in positioning filaments in the bulbs of filament lamps in their proper focal position, said tool comprising:

- (a) a base member,
- (b) a parabolic reflector carried by said base member,
- (c) a seat defined by said base member and adapted to receive the bulbs of said lamps,
- (d) means for initially adjusting said reflector relative to said seat by use of a master filament lamp of the same size as said lamps to be adjusted and having a generally perfectly focused filament,
- (e) means for releasably retaining the bulbs of lamps to be adjusted against said seat, said means comprising a plurality of inwardly biased roller elements each one positioned adjacent a different one of said seat elements and said roller elements being located longitudinally of said base member for engagement with this bulb surfaces of the lamps to be adjusted at positions over the greatest transverse diameter of the bulbs, and
- (f) whereby the filaments of the lamps may be adjusted by moving the stem until a given portion of the filament intersects a similarly given portion of the filament image produced by said reflector when viewing the filament from a generally lateral viewpoint.

2. A tool for use in positioning filaments in the bulbs of filament lamps in their proper focal position, said tool comprising:

- (a) a base member,
- (b) a parabolic reflector carried by said base member,
- (c) a seat defined by said base member and adapted to receive the bulbs of said lamps,
- (d) means for initially adjusting said reflector relative to said seat by use of a master filament lamp of the same size as said lamps to be adjusted and having a generally perfectly focused filament,
- (e) means for releasably retaining the bulbs of lamps to be adjusted against said seat,
- (f) whereby the filaments of the lamps may be adjusted by moving the stem until a given portion of the filament intersects a similarly given portion of the filament image produced by said reflector when viewing the filament from a generally lateral viewpoint, and
- (g) means for ejecting said adjusted lamps from said tool.

3. A tool for use in positioning filaments in the bulbs of filament lamps in their proper focal position, said tool comprising:

- (a) a base member,
- (b) a parabolic reflector carried by said base member,
- (c) a plurality of spaced seat elements defined by said base member and adapted to receive the bulbs of the lamps to be adjusted,
- (d) means mounting said reflector within said base member for longitudinal adjustment relative to said seat elements by use of a master filament lamp of the same size as said lamps to be adjusted and having a generally perfectly focused filament,
- (e) means for releasably retaining the bulbs of the lamps to be adjusted against said seat elements, said means comprising a plurality of inwardly biased roller elements each one positioned adjacent a different one of said seat elements and said roller elements being located longitudinally of said base member for engagement of the bulb surfaces of the lamps to be adjusted at positions over the greatest transverse diameter of the bulb,
- (f) whereby the filaments of the lamps may be adjusted by moving the stem until a given portion of the filament intersects a similarly given portion of the filament image produced by said reflector when viewing the filament from a generally lateral viewpoint, and
- (g) means for ejecting said adjusted lamps from said tool.

4. The method of positioning the filament in the bulb of a filament lamp in its proper focal position, said method comprising:

- (a) placing the stem-carried filament within the bulb,
- (b) positioning the outer generally spheroidal surface of the filament-carrying bulb in a seat which has been preadjusted relative to a parabolic reflector by use of a master filament lamp of the same size as said lamp to be adjusted and having a generally perfectly focused filament, and
- (c) adjusting the position of the filament of the lamp to be adjusted by moving the stem until a given portion of the filament intersects a similarly given portion on the filament image produced by said reflector when viewing said filament from a generally lateral viewpoint.

5. The method of positioning the filament in the bulb of a filament lamp in its proper focal position, said method comprising:

- (a) placing the stem-carried filament within the bulb,
- (b) positioning the outer generally spheroidal surface of the filament-carrying bulb in a seat which has been preadjusted relative to a parabolic reflector by use of a master filament lamp of the same size as said lamp to be adjusted and having a generally perfectly focused filament,
- (c) adjusting the position of the filament of the lamp

to be adjusted by moving the stem until a given portion of the filament overlaps a similarly given portion on the filament image produced by said reflector when viewing said filament from a generally lateral viewpoint.

- 5 (d) heating and sealing the stem to the bulb neck, and
 (e) before said stem and bulb neck have cooled, readjusting the position of the filament by moving the stem until a given portion of the filament intersects a similarly given portion on the filament image produced by said reflector when viewing the filament from a generally lateral viewpoint.

6. The method of positioning the filament in the bulb of the filament lamp in its proper focal position, said method comprising:

- (a) placing the stem-carried filament within the bulb,
 (b) positioning the outer generally spheroidal surface of the filament-carrying bulb in a seat which has been preadjusted relative to a parabolic reflector by use of a master filament lamp of the same size and having a generally perfectly focused filament,
 (c) adjusting the position of the filament of the lamp to be adjusted by moving the stem until a given portion of the filament overlaps a similarly given

10

15

20

portion on the filament image produced by said reflector when viewing said filament from a generally lateral viewpoint,

- (d) heating and sealing the bulb neck to the filament carrying stem,
 (e) removing the excess neck portion outwardly of its seal to the stem,
 (f) after reheating the bulb neck and stem, readjusting the position of the filament by moving the stem until a given portion of the filament intersects a similarly given portion on the filament image produced by said reflector when viewing the filament from a generally lateral viewpoint,
 (g) evacuating the bulb and thereafter sealing the evacuating portion of the stem, and
 (h) mounting a base onto the bulb.
